UNITED STATES PATENT OFFICE.

EDWARD J. HALL, OF PHILADELPHIA, PENNSYLVANIA.

TOY CHANDELIER.

SPECIFICATION forming part of Letters Patent No. 269,283, dated December 19, 1882.

Application filed October 20, 1882. (No model.)

To all whom it may concern:

Be it known that I, EDWARD J. HALL, a citizen of the United States, residing at Philadelphia, in the county of Philadelphia and State of Pennsylvania, have invented certain new and useful Improvements in Toy Chandeliers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to toy chandeliers to be used in lighting up Christmas-trees and for other similar purposes. The novelty consists in the manner of constructing the chandelier, as will be hereinafter shown, and more particularly pointed out in the claims.

20 The accompanying drawings illustrate the invention.

Figure 1 is a side elevation of the device, and Fig. 2 shows the several layers of tin composing the main stem in a plane condition edgewise, in a similar condition sidewise, and twisted.

25 A is the main stem or body of the chandelier. This stem is formed by taking four narrow strips of tin or similar metal of equal width, fastening them together at one end, and twisting them in the manner shown until the desired length is secured. The parts are then separated, and after being twisted separately 30 are bent so as to form the arms B B.

35 On the end of each arm is soldered the cup C, which is used to catch the melted grease as it flows from the burning candle. In the center of the cup C is fastened a cylindrical socket, 40 d, into which the candle is placed. The upper

end of the stem A is bent so as to form the loop e, by which the chandelier may be suspended. To give a finish to the loop e the small tin disk f is placed around the bottom thereof. a a are single narrow strips of tin, 45 twisted in the same manner as the stem A, and fastened at the top of the chandelier, underneath the disk f, extending from thence to the arms B B, as shown in the drawings, Fig. 1. They help to support the arms and give a 50 finish to the chandelier. The number of lights on the chandelier is regulated by the number of strips used to form the body or stem.

A chandelier constructed in the manner herein described makes a cheap, beautiful toy, 55 and when the candles are burning the bright surface of the twisted tin reflects the light at different angles, giving the appearance of glass.

Having thus described my invention, what I claim as new, and desire to secure by United 60 States Letters Patent, is—

1. A toy chandelier formed with a main stem and divergent supporting-arms, composed of strips of tin or other metal twisted and united substantially in the manner set forth. 65

2. A toy chandelier in which the narrow strips of metal used to form the body thereof are continued separately and bent so as to form the arms, substantially as shown and described. 70

3. The body A, having arms B B, in combination with socket d, substantially as and for the purpose described.

In testimony whereof I affix my signature in presence of two witnesses.

EDWARD J. HALL.
